UNITED STATES PATENT OFFICE.

THOMAS F. LAWTON, OF NEW YORK, N. Y., ASSIGNOR TO CONE COMPANY OF AMERICA,
OF NEW YORK, N. Y.

DESIGN FOR AN ICE-CREAM CONE.

59,603.

Specification for Design.

Patented Nov. 8, 1921.

Application filed November 23, 1920. Serial No. 426,087. Term of patent 14 years.

To all whom it may concern:

Be it known that I, THOMAS F. LAWTON, a citizen of the United States, residing at New York, in the county of New York and State of New York, have invented a new, original, and ornamental Design for Ice-Cream Cones, of which the following is a specification, reference being had to

the accompanying drawing, forming part thereof.

The figure is a plan view of an ice cream cone, showing my new design.

I claim:

The ornamental design for an ice cream cone, as shown.

THOMAS F. LAWTON.
